MULTIPLE DOOR CONSTRUCTION

Clarence G. Johnson and Herbert C. Blodgett,
Hartford City, Ind., assignors to Overhead Door
Corporation, Hartford City, Ind., a corporation
of Indiana

Application August 4, 1931, Serial No. 555,109

14 Claims. (Cl. 20—20)

The present invention pertains to a novel door construction wherein a wide door opening is provided with two or more mutually adjacent doors of the type which are opened by raising. In such a construction it is evident that a vertical guide means between the doors is necessary.

The principal object of the invention is to provide, in such a construction, efficient means for removing the intermediate guide means entirely out of the door opening so that the latter may be entirely cleared. Obviously, either door may be opened separately when it alone provides sufficient clearance for the particular purpose at hand. The intermediate guide means and the adjacent doors are lifted only when a clear opening having a width greater than one door is desired.

The intermediate door guiding means is in the nature of a mullion carrying rails for guiding the immediately adjacent edges of the adjacent doors. The equipment for moving the mullion out of the door opening includes a horizontal track extending inwardly from the door opening at a point near the upper end of the mullion when the latter is disposed in the door opening. A carriage rides on the track and has a hinge connection to the upper end of the mullion, and suitable manual or power means is provided for propelling the carriage on the track and for drawing a cable which is connected to the lower end of the mullion, whereby the latter is guided in a substantially vertical path while the upper end is shifted horizontally. The upper and lower ends of the mullion travel at varying and unequal speeds at different times, and accordingly the power devices must be constructed to run at corresponding rates. In keeping with this necessity, the power devices are equipped with yielding friction clutches, so that the devices may be initially geared together and driven from a single motor but at the same time permitted to slip in order not to overrun the speeds of the respective ends of the mullion on which they operate.

The invention further includes an automatic safety stop device which prevents the doors from dropping to closed position after they have been raised. The stop device is rendered inoperative on lowering of the mullion, after which the doors may be lowered. In other words, the lowering of the mullion is a pre-requisite to the closing of the doors, either intentionally or accidentally.

The invention is fully disclosed by way of example in the following description and in the accompanying drawings, in which—

Figure 1 is an inside elevation of a door constructed according to the invention;

Fig. 2 is a section on the line 2—2 of Figure 1; Fig. 3 is a section in the same plane as Figure 2, showing the door in open position; Fig. 4 is a section on the line 4—4 of Figure 1; Fig. 5 is a section on the line 5—5 of Figure 1; Fig. 6 is a section on the line 6—6 of Figure 3; Fig. 7 is a section on the line 7—7 of Figure 1; Fig. 8 is a section on the line 8—8 of Figure 2; Fig. 9 is an enlarged detail of Figure 7; and Fig. 10 is a section on the line 10—10 of Figure 9.

Reference to these views will now be made by use of like characters which are employed to designate corresponding parts throughout.

In Figure 1 is illustrated a door frame structure of such width as to require two separate doors, each of which is of sufficient width to permit an automobile or truck to pass. The invention enables the clearing of the entire door opening from side to side so that an opening of double standard width may be provided if desired or necessary. Accordingly, there is provided a central post or mullion 2 of flanged channel cross section adapted to occupy a vertical position in the center of the doorway, as shown in Figure 1 and mounted in such a manner to be swung out of the doorway by the means presently to be described.

At the sides of the doorway are mounted rails comprising each a substantially vertical section 3 and a horizontal section 4 extending rearwardly from the upper end of the vertical section. Directly over the post or mullion 2 is provided a fixed header bracket 5 which forms a split joint 6 with the mullion when the latter is in vertical position. At the mullion, horizontal rail sections 7 having downwardly curved forward ends 8 extend rearwardly or inwardly from the header bracket 5 in substantially parallel relation to the sections 4 and may be supported, for example, by the header bracket at the forward end and by hangers 9 at the rear end. A straight vertical track 10 lies below the rail sections 7 to serve a purpose which will presently be described, and is supported, for example, at one end by hangers 11 suspended from the sections 7 and at the other end by extensions 9' of the members 9.

The support for the mullion 2 comprises a carriage 12 riding on the track 10 and having a depending hinge arm 13 having its lower end 14 pivotally attached to a complementary hinge bracket 15 carried by the upper edge of the mullion. The vertical position of the mullion is determined by the reception of the lower end thereof between forward and rear stops 16 and 17 respectively at the floor and by the closing of the

split joint 6 at the upper end. The mullion carries substantially vertical rails 18 similar to the vertical sections 3 and adapted to communicate with the horizontal sections 7 to form continuous rails equal and parallel to the continuous members 3, 4.

The rails may be grouped into pairs at opposite sides of the mullion 2, each pair constituting a track. Between the rails of each track is disposed a door consisting of superimposed panels 19 joined together by hinges 20 on horizontal axes. The hinges are disposed at the ends of the panels and carry rollers 21 riding in the vertical rail sections.

Each door is counterbalanced by a pair of coil springs 22 extending horizontally inward of the building structure and having their rear ends secured to the hangers 9. The forward ends carry pulleys 23. Idler pulleys 24 are mounted on the fixed door structure and are engaged by cables 25 secured respectively to the lower corners of the door, passing over the alined pulleys 24 and 23 and finally secured as at 26 to the fixed frame structure.

Either door may be opened by lifting it upwardly until it is supported entirely on the horizontal part of its track. In order to clear the entire door opening, both doors are first raised in this manner, and may be actuated manually because of the counterbalancing springs 22. The mullion 2, carrying the separate rail sections 18 may now have its upper end moved rearwardly on the track 10, either manually or mechanically, and the lower end also raised to approximately the height of the track 10 by the time the carriage 12 has reached its rearward position, whereby the mullion and associated rail sections are transferred entirely out of the door opening and to the position shown in Figure 3.

The means for effecting this movement of the mullion includes plates 27 at the rear end of the track 10 with a pair of parallel shafts 28 and 29 journaled therein as shown more clearly in Figure 8. A reversible electric motor 30 is disposed adjacent the shaft 28 and is geared to a pulley 31 on the shaft by means of a belt 32. Obviously the shaft may be propelled manually if desired.

The shafts 28 and 29 carry spur gears 33 and 34 respectively keyed thereto and in mesh with each other. Adjacent the gears, the shafts carry sprocket wheels 35 and 36 respectively, with the friction disks 37 inserted between each spur gear and the adjacent sprocket wheel. The spur gears are held under pressure against the friction material and the gears by springs 38 surrounding the shafts and adjusted by lock nuts 39.

The carriage 12 carries a sprocket 40 in line with the sprocket 36 and connected thereto by an endless sprocket chain 41. Thus, when the sprocket 36 is turned through the gearing already described and in the proper direction, the carriage and upper end of the mullion are drawn rearwardly along the track 10.

Angle brackets 42 are secured to the header bracket 5 and carry an idler pulley 43 disposed above the mullion when in closed position and also substantially in line with the sprocket 35. A sprocket chain 44 is passed over the sprocket 35, carrying at one end a counterweight 45 and having its forward end attached to a cable 46 which passes over the pulley 43 and has its other end attached to a bracket 47 at the lower end of the mullion as may be seen in Figure 2. Thus, when the sprocket 35 is actuated, the lower end

of the mullion is raised as the upper end thereof is drawn rearwardly through the action of the sprocket 36 and chain 41 as already stated. In order to determine a definite path for the mullion in moving from the vertical to a horizontal position, a link 48 has its upper end pivoted at 49 to the brackets 42 and its lower end pivoted to a bracket 50 at substantially the midpoint of the mullion.

As the mullion moves from the position shown in Figure 2 to that shown in Figure 3, it will be evident that the respective velocities of the upper and lower ends are not always equal. Therefore, a direct drive between the shafts 28 and 29 would be seriously defective, and for this reason the drive between the spur gears 33 and 34 and their respective sprockets 35 and 36 is of frictional nature, permitting slippage as the speeds of the chains 41 and 42 vary. Obviously, the mullion is lowered by operating the motor 30 in the reverse direction.

When operated manually, the mullion is locked in vertical position, as shown in Figure 9, by means of a bolt 51 slidably mounted in a housing 52 at the upper end of the mullion and moved by a spring 53 into a notch 54 cut in the lower end of the bracket 5. The bolt is released from the bracket 5, prior to the lifting movement of the mullion, by pulling on a chain 54 depending from the bolt and passing through a slot 55 in the inner side of the mullion. The lower end of the mullion is located by the stops 16 and 17, as already indicated. The upper end, after closing the split joint 6, is positioned laterally by brackets or lugs 56 depending from the header bracket 5, as shown more clearly in Figs. 7 and 9.

In the base corners of the channel bracket 5 are secured pivot brackets 57 slightly above the lower end of the bracket. To these members 40 are pivotally attached segmental stop members 58 adapted to swing into slots 59 in the sides of the bracket 5. Springs 60 connecting the stop members to the bracket tend to move the stop members through the slots or against the adjacent vertical rail sections 18 carried by the mullion as shown in Figure 10. Thus, when these rail sections are swung with the mullion to a horizontal position, they disengage the stops 58, whereupon the latter move into the downward path of the rails 18 and corresponding rollers 21 and prevent the doors from falling. When, however, it is desired to lower the doors, the mullion is first returned to its vertical position. In so moving, the rails 18 carried by the mullion have a cam action against the outer edges of the stops 58, returning them to the position shown in Figure 10, whereupon the doors may be returned to closed position. In other words, the doors cannot be closed until the mullion has been returned to vertical position.

Although a specific embodiment of the invention has been illustrated and described, it will be understood that various alterations in the details of construction may be made without departing from the scope of the invention, as indicated by the appended claims.

What we claim is:—

1. In a door structure having a door opening, a mullion adapted to divide said opening, means for moving said mullion out of said opening, a fixed member over said mullion, fixed rails terminating at said member, doors at opposite sides of said mullion and having rollers adapted to ride in said rails, stops carried by said fixed

member and adapted normally to project into the path of said rollers, cooperating rails comprised in said mullion and adapted to aline with the first named rails when the mullion is in the opening, said stops being engaged by a part of said mullion to retract said stops from the path of said rollers, on moving the mullion into said opening.

2. In a door structure having a door opening, a mullion adapted to divide said opening, means for moving said mullion out of said opening, a fixed member over said mullion, fixed rails terminating at said member, doors at opposite sides of said mullion and having rollers adapted to ride in said rails, stops carried by said fixed member and adapted normally to project into the path of said rollers, cooperating rails carried by the mullion and adapted to aline with the first named rails when the mullion is in the opening, said stops being engageable by said cooperating rails to retract the stops from the path of said rollers, on moving said mullion into said opening.

3. In a door structure having a door opening, a mullion adapted to divide said opening, means for moving said mullion out of said opening, a fixed member over said mullion, fixed rails terminating at said member, doors at opposite sides of said mullion and having rollers adapted to ride in said rails, stops carried by said fixed member and adapted normally to project into the path of said rollers, cooperating rails comprised in said mullion and adapted to aline with the first named rails when the mullion is in the opening, said stops being engaged by a part of said mullion to retract said stops from the path of said rollers, on moving the mullion into said opening, and a spring latch adapted to lock said mullion to said fixed member when said mullion is in said opening.

4. In a door structure having a door opening, a mullion adapted to divide said opening, means for guiding and moving the upper end of said mullion inwardly from said opening, doors in said opening at opposite sides of said mullion, substantially vertical guiding means for said door in said mullion, and substantially horizontal guiding means for said door supported by said structure and communicating with the vertical guiding means at the upper ends thereof.

5. In a door structure having a door opening, a mullion adapted to divide said opening, guide members mounted on said mullion, guide members mounted on said door structure above said opening and registering with the guides on said mullion, doors having means extending into the guides on said mullion and adapted to be moved into the guides above said opening, means for guiding and moving the upper end of said mullion inwardly from said opening, and means for guiding the lower end of said mullion in a substantially vertical line.

6. In a door structure having a door opening, a mullion adapted to divide said opening, guide members mounted on said mullion, guide members mounted on said door structure above said opening and registering with the guides on said mullion, doors having means extending into the guides on said mullion and adapted to be moved into the guides above said opening, means for guiding and moving the upper end of said mullion inwardly from said opening, and means for lifting the lower end of said mullion.

7. In a door structure having a door opening, a mullion adapted to divide said opening, guide

members mounted on said mullion, guide members mounted on said door structure above said opening and registering with the guides on said mullion, doors having means extending into the guides on said mullion and adapted to be moved into the guides above said opening, means for guiding and moving the upper end of said mullion inwardly from said opening, means for lifting the lower end of said mullion, and friction clutches in both of said last two mentioned means.

8. In a door structure having a door opening, a mullion adapted to divide said opening, guide members mounted on said mullion, guide members mounted on said door structure above said opening and registering with the guides on said mullion, doors having means extending into the guides on said mullion and adapted to be moved into the guides above said opening, means for guiding and moving the upper end of said mullion inwardly from said opening, means for lifting the lower end of said mullion, friction clutches in both of said last two mentioned means, said last two mentioned means being geared together, and a power device for driving one of said means.

9. In a door structure having a door opening, a mullion adapted to divide said opening, guide members mounted on said mullion, guide members mounted on said door structure above said opening and registering with the guides on said mullion, doors having means extending into the guides on said mullion and adapted to be moved into the guides above said opening, a horizontal track over said mullion, a carriage riding on said track and hinged to the upper end of said mullion, and means for propelling said carriage on said track.

10. In a door structure having a door opening, a mullion adapted to divide said opening, guide members mounted on said mullion, guide members mounted on said door structure above said opening and registering with the guides on said mullion, doors having means extending into the guides on said mullion and adapted to be moved into the guides above said opening, a horizontal track over said mullion, a carriage riding on said track and hinged to the upper end of said mullion, means for propelling said carriage on said track, and means for guiding the lower end of said mullion in a substantially vertical line.

11. In a door structure having a door opening, a mullion adapted to divide said opening, guide members mounted on said mullion, guide members mounted on said door structure above said opening and registering with the guides on said mullion, doors having means extending into the guides on said mullion and adapted to be moved into the guides above said opening, a horizontal track over said mullion, a carriage riding on said track and hinged to the upper end of said mullion, means for propelling said carriage on said track, and means for lifting the lower end of said mullion.

12. In a door structure having a door opening, a mullion adapted to divide said opening, guide members mounted on said mullion, guide members mounted on said door structure above said opening and registering with the guides on said mullion, doors having means extending into the guides on said mullion and adapted to be moved into the guides above said opening, means for guiding and moving the upper end of said mullion inwardly from said opening, means for lifting the lower end of said mullion, and a link ar-

ticulated to said mullion and to said structure at a point above said mullion.

13. In a door structure having a door opening, a mullion adapted to divide said opening, guide members mounted on said mullion, guide members mounted on said door structure above said opening and registering with the guides on said mullion, doors having means extending into the guides on said mullion and adapted to be moved 10 into the guides above said opening, a horizontal track over said mullion, a carriage riding on said track and hinged to the upper end of said mullion, means for propelling said carriage on said track, means for lifting the lower end of said mullion, and a link articulated to said mullion and to said structure at a point above said mullion.

14. In a door and door-way construction, the combination with a wall forming an opening, of a member normally disposed vertically and dividing said opening into passages and bodily mov-

able into an inoperative position, means for removably supporting said member in normal position, a horizontal member associated with the upper end of said first mentioned member and extending inwardly from said opening, pairs of 5 tracks carried by said wall and said members, a door slidable in each pair of tracks and adapted to close and open the adjacent passage, and means for movably supporting said first mentioned member when disengaged from its supporting 10 means for movement to and from its inoperative position, said means comprising a device movable on said horizontal member and connected to the upper end of said first mentioned member and means connected to the lower end of said first 15 mentioned member and serving to guide and counterbalance such end.

CLARENCE G. JOHNSON.
